Primary Examiner — John Windmuller*Assistant Examiner* — Luqman McNeil(74) *Attorney, Agent, or Firm* — Bose Corporation(57) **CLAIM**

The ornamental design for a remote control, substantially as shown and described.

DESCRIPTION

FIG. 1 is a perspective view of a remote control as seen from the front, top and right side;

FIG. 2 is a perspective view thereof as seen from the front, bottom, and left side;

FIG. 3 is a perspective view thereof as seen from the back, top, and left side;

FIG. 4 is a top view thereof;

FIG. 5 is a bottom view thereof;

FIG. 6 is a back view thereof;

FIG. 7 is front view thereof;

FIG. 8 is a left side view thereof; and,

FIG. 9 is a right side view thereof.

The dotted line portions of the drawings represent environmental structure only and do not form part of the claimed design.

1 Claim, 7 Drawing Sheets(56)
